UNITED STATES PATENT OFFICE.

DAVID D. REESE, OF SCRANTON, PENNSYLVANIA, ASSIGNOR OF ONE-HALF
TO EUGENE D. CORWIN, OF SCRANTON, PENNSYLVANIA.

FIRE-POT FOR BLACKSMITHS' FORGES.

SPECIFICATION forming part of Letters Patent No. 697,275, dated April 8, 1902.

Application filed February 19, 1901. Serial No. 47,920. (No model.)

To all whom it may concern:

Be it known that I, DAVID D. REESE, a citizen of the United States, residing at Scranton, in the county of Lackawanna and State of Pennsylvania, have invented certain new and useful Improvements in Fire-Pots for Blacksmiths' Forges, of which the following is a specification, reference being had therein to the accompanying drawings.

10 My invention relates to fire-pots for open hearths, such as are used by ordinary blacksmiths for heating irons to be welded and forged; and the objects of the invention are to provide a fire-pot easily separated and removable in parts or pieces, to provide an article of the kind which may be adjusted to any ordinary blacksmith's hearth, and to provide a more efficient and indestructible device of the kind than those heretofore in use.

15 To these ends my invention consists of the construction, combination, and arrangement of the parts as specified and shown in the accompanying drawings, in which—

Figure 1 is a view in isometric perspective 25 of one of my fire-pots assembled and ready to be inserted onto a blacksmith's grate. Fig. 2 is a cross-section, taken on the line $x-x$, of one of the members as shown in Fig. 1. Fig. 3 is a detail view of the construction of an 30 end of one of the members entering into the device. Fig. 4 is a detail view of an end of another member adapted to match that shown in Fig. 3. Fig. 5 is a general view of a blacksmith's hearth, showing my device in position.

35 Similar characters of reference denote like and corresponding parts throughout the several views.

In the drawings, 1 and 1' represent opposite sides or pieces of my fire-pot and are made 40 exactly alike. 2 and 2' represent the end pieces thereof, which are constructed to match at the corners with the pieces 1 and 1' aforesaid, the whole making a rectangular receptacle or inclosure adapted to be set or built 45 into a hearth, as shown in Fig. 5, surrounded by bricks or other suitable material. The materials from which the fire-pot itself is constructed may be fire-brick, graphite, stone, carbon, or any other suitable material, the 50 principal requirement being that they shall be of a very high fusing-point above that of

iron or the ordinary metals. The corners are matched by means of a groove 6, cut in the opposite ends of 1 and 1', into which a tongue 5 of the pieces 2 2' is adapted to slide, the 55 faces 4 and 4' coinciding, so as to complete a clean exposure of flat surface inwardly. Each of the parts entering into the composition of my device is quadrangular in cross-section, as shown in Fig. 2, having the longest side 60 thereof, 3, arranged to slope outwardly from the middle, the outer side 3' being perpendicular with the top and bottom sides, so as to conveniently fit into masonry or brickwork.

My device, if made from stone, can be sawed 65 out by the usual method; but I prefer to have it made from fire-clay, in which case molds are to be used and the material placed into them in a plastic state, pressed, and properly fired, great care being taken that they 70 may not be allowed to warp in the burning. In the use of the device the grate 8 over which they are to be used should be cleared and the parts laid into position over the top thereof, and then they should be built around 75 by bricks or other suitable hearth-making material until the top of the hearth is even or flush with the top faces of the pieces of the fire-pot, as is illustrated in Fig. 5. It may be used, therefore, in connection with any blow- 80 ing device, as 10. Any ordinary hearth 9, provided with a blower 10 and grate 8, may thus be fitted out with my device, which is adapted to be sold as an article of manufacture.

It should be noticed that the parts compos- 85 ing my fire-pot as thus described are removable by sliding vertically upward, so that if any of the pieces become damaged they may be easily slid out and a sound piece substi- 90 tuted in place of the removed piece.

I do not wish to be confined to the exact construction of the corners and sides of the parts of my device, as it is evident that some of them may be varied without departing from the general spirit of the invention.

What I do claim, and desire to secure by Letters Patent, is—

1. The herein-described fire-pot for blacksmiths' hearths, comprising several pieces of refractory material quadrangular in cross-section, the said pieces being arranged so as to form an inclosure, and the pieces joined by

tongues and grooves cut in a vertical direction, whereby the pieces are easily separable, removable and replaceable by sliding in a vertical direction, substantially as and for the purpose specified.

2. In combination with a blacksmith's hearth and grate, a fire-pot constructed from pieces of refractory material, said pieces superposed on said grate and having their ends joined so as to form an inclosure, the joining ends interlocked by means of tongues and

grooves cut in a vertical direction, and the outer exposed sides of said pieces being vertical planes whereby the pieces are easily separable, removable and replaceable by sliding vertically, substantially as specified. 15

In testimony whereof I affix my signature in presence of two witnesses.

DAVID D. REESE.
